UNITED STATES PATENT OFFICE.

ALMYR L. NEWMAN, OF WARWICK, RHODE ISLAND, ASSIGNOR TO A. L. NEWMAN COMPANY, OF PROVIDENCE, RHODE ISLAND, A CORPORATION OF RHODE ISLAND.

FASTENING DEVICE FOR WRIST-WATCH STRAPS, BANDS, AND BRACELETS.

Application filed August 3, 1926. Serial No. 126,803.

This invention relates to buckles, clasps, or other fastening devices for use with wrist-watch straps, bands, or bracelets and similar articles.

5 One object of the invention is to provide a buckle or clasp with extendible means for attaching it to the end of the strap, band, or bracelet, said means adapted to be unfolded or opened out to extend the length of the strap, 10 band or bracelet whereby it may be slipped off from the wrist without unfastening the buckle or clasp.

A particular object of the invention is to provide a lock or fastening-device on the extendible means which, when the latter is folded into closed relation, will positively hold the parts from being accidentally opened or extended.

Another object of the invention is to provide a fastening-device on the extendible means which is automatically locked when the parts are folded together and which may be conveniently released or unlocked under the pressure of the fingers.

20 Another object of the invention is to provide a fastening-device on the extendible means which is compact and inconspicuous and while normally hidden from view is easily accessible for manual operation.

25 Further objects of the improvement are set forth in the following specification which describes a preferred embodiment of the invention as illustrated by the accompanying drawings. In the drawings:

30 Fig. 1 is a view showing a wrist-watch with a two-part strap or wrist-band attached thereto and illustrating my improved extendible buckle or clasp with the parts shown in closed relation;

35 Fig. 2 is a similar view showing the extendible member of the clasp or buckle in opened relation;

40 Fig. 3 is an enlarged front view of the buckle showing the ends of the strap fastened together thereby;

45 Fig. 4 is an enlarged edge view of the same showing the extendible member in closed relation;

50 Fig. 5 is a similar view showing the parts of the extendible member partly unfolded;

55 Fig. 6 is a front view of the buckle showing the extendible member fully opened;

Fig. 7 is a perspective view of the same showing the method of operation of the device; and

Fig. 8 is a sectional detail view of the locking-device for the extendible member taken on line 8—8 of Fig. 6.

In accordance with the general custom, 60 wrist-watches are usually provided with straps, bands or bracelets having buckles or clasps for securing them to the wrist of the wearer. In Figs. 1 and 2 of the present drawings 2 designates a conventional type of 65 wrist-watch having a two-part band or strap 3 and 4 attached to the sides thereof. One length 3 of the strap is usually provided with a clasp or buckle 5 and the end of the other strap-length 4 may be punched with holes to 70 adapt it to be held by the tongue 6 of the buckle as illustrated in Fig. 3. Heretofore it has been the common practice to attach the buckle or clasp fixedly to the end of one strap-length and with this arrangement, in applying 75 the watch to the wrist or removing it therefrom, it is necessary to unbuckle or unclasp the strap or band. Only one hand can be used for buckling and unbuckling the strap so that the operation is somewhat awkward and frequently results in dropping the watch 80 and breaking it.

It has before been proposed to provide 85 extendible means or a folding element arranged between the end of the strap-length and the buckle so that the whole strap may be lengthened or extended without unbuckling it, but heretofore such means have not been entirely satisfactory due to the fact that the extendible member may become accidentally opened or unfolded and the watch dropped off and 90 broken or even lost. A particular object of the present invention, therefore, is to provide a simple, compact fastening or locking-device for the extendible means which snaps into place to hold said means against accidental opening or extension, while being 95 convenient to release with one hand when it is desired to remove the watch from the wrist.

As shown in Figs. 4 to 7 of the present drawings the extendible means for the buckle 100 5 comprises two relatively flat metal straps or plates 8 and 9 which are joined together at their ends by a hinge 10 pivotally connected by a pin or pintle 11. At the free end of the hinged plate 8 is a fork-member 105 12 having ears 13 adapted to straddle the edges of the looped end of the strap-length 3 and pierced to receive a suitable pin 14 inserted through the loop to attach the end of the strap to the plate. The plate 8 is widened 110

where it joins the end-member 12 and is provided with a pierced aperture 15, see Figs. 6 and 7, adapted to receive the catch of the locking-device to be later described.

The opposite hinged plate 9 is attached at its end to the pivot-pin 16 of the buckle-tongue 6. As shown particularly in Figs. 6 and 7 the pin 16 extends through ears 17 on the sides of the buckle-frame 5, and suitable ears 18 on the plate 9 are adapted to straddle the buckle-tongue 6 within the sides of the frame to receive the pin passing therethrough. Through this last-described arrangement the hinged plate 9 is pivoted to the buckle to adapt it to swing in relation thereto whereby it may be folded against its connected plate 8 in the manner illustrated in Fig. 4. Preferably, the two plates 8 and 9 are curved to adapt them to conform more or less to the shape of the wrist when the parts are folded together, see Fig. 1.

My improved locking-device for the extendible means of the buckle is housed in a flat casing 20 located on either of the hinged plates, but preferably on the member 9 adjacent the point of attachment of the latter to the buckle 5. As shown more particularly in Figs. 6 and 8, two ears 21 are bent over from the opposite edges of the plate 9 to project forwardly at right-angles to the plane of its main portion. Extending between the ears 21 and soldered or otherwise secured thereto is a folded strip of sheet-metal forming the casing or housing 20 for the slidable locking-element or latch 22. The latch 22 consists of a flat strip of metal adapted to fit within the sides of the housing 20 and provided with a narrowed extension 23 at its end which projects through a slot or perforation in one of the ears 21. The extension 23 provides a finger-piece for operating the latch and is preferably formed with a notch 24 in its end for receiving the finger nail. The latch 22 has a hooked catch 25 which projects outwardly through a rectangular slot or aperture 26 in the front of the housing 20. The projection or catch 25 has a beveled end adapted for entrance through the rectangular aperture 15 in the opposite hinged plate 8 to engage its shoulder or hook over the edge thereof, in the manner as illustrated in Fig. 8, whereby to lock the two plates together. A coiled wire spring 27 is held in the housing 20 beneath the end of the latch 22 and tends to normally slide the latter upwardly as shown in Fig. 6.

My improved device is applied to use in the manner as next explained. With the extendible means and its buckle attached to the end of the strap length 3, as previously described, the two hinged plates 8 and 9 are folded together and locked in closed relation by means of the catch 25 projecting through the orifice 15 and engaged over its edge. The watch is then applied to place with the strap

lengths 3 and 4 encircling the wrist, the end of the free length 4 being inserted through the buckle 5 and the tongue 6 of the buckle projected through the proper hole in the strap to hold it tight around the wrist. After the strap has once been adjusted in this manner it is unnecessary to loosen it from the buckle unless the strap is to be taken up another hole after stretching. That is to say, in removing the watch from or applying it to the wrist it is unnecessary to unbuckle the strap, the procedure being as follows: When it is desired to remove the watch from the wrist the wearer inserts his finger nail in the notch 24 at the end of latch 22 and by exerting a slight pressure thereon the latch may be slid against the tension of its spring 27 to disengage its catch 25 from the edge of the slot 15 in the plate-member 8. After the catch has been released in this manner the two plate-members 8 and 9 may be swung apart as shown in Figs. 5 and 7, and after they have been extended to their full length as illustrated in Figs. 2 and 6 the strap may be slid off over the hand. In applying the watch to the wrist again the reverse procedure is followed, the extended plates 8 and 9 allowing the strap to be slipped on over the hand.

After the strap is in place on the wrist the member 9 is simply folded against the member 8 in the manner shown in Fig. 4, whereupon the locking-device or latch 22 on the member 9 automatically locks in engagement with the member or plate 8 whereby to hold the parts in closed relation. In this way the latch acts automatically to lock the parts of the extendible member together to prevent accidental opening so that the two sections of the strap are buckled together as securely as if each of itself were permanently secured to the buckle. My improved device therefore insures against accidental or unwarranted removal of the watch and thus guards against loss or breakage, while at the same time making for much greater convenience in applying the watch to and removing it from the wrist. It will be observed that the improved device is extremely simple in construction, practically proof against derangement or getting out of order, compact in size and inconspicuous, while yet convenient for manual operation in applying the watch to or removing it from the wrist.

While I have herein shown and described my improvement as applied to a conventional type of wrist-strap having a usual form of buckle it is to be understood that the extendible member and its locking-means is adapted for use with other types of straps, bands, or bracelets and with other clasping-means. Various other modifications may be made in the form and structure of the device without departing from the scope or spirit of the invention and therefore, without limiting myself in this respect.

I claim:

1. In a device of the type specified, the combination of hinged members adapted to be folded together in overlying relation, means for attaching one end of a strap, band, or bracelet to the free end of one member, means on the free end of the other member for adjustably fastening the other end of the strap-length thereto, a positively acting slideable latch on one member adapted to engage the other member to lock said members in overlying relation, and manually-operable means for sliding said latch to release the lock to permit extension of said members.
2. A device of the type specified comprising opposite hinged members adapted to be folded one against the other in overlying relation, means for attaching one end of a strap, band, or bracelet to the free end of one member, means on the other member for adjustably attaching the other end of the strap-length thereto, a latch slideable at the free end of one of said members and adapted to positively engage the opposite member to lock said members in folded relation, resilient means for holding said latch in locked position, and manually-operable means for releasing said latch to permit the members to be opened or unfolded.
3. In a device of the type specified, the combination of a pair of hinged plates adapted to be folded into overlying relation, means at the free end of one of said plates for attaching it to one end of a strap, band, or bracelet, a buckle at the end of the opposite plate for attaching the other end of the strap-length thereto, a housing on one of said plates, a latch slideable in said housing and adapted to positively engage with the other plate to lock said plates in closed relation, a spring in

said housing for sliding the latch, and means for manually operating the latch to unlock said plates to permit them to be opened into extended relation.

4. In a device of the type specified, the combination of a pair of plates hinged together at one end, means at the opposite free end of one of the plates for attaching it to one end of a strap, band, or bracelet, a buckle hinged to the opposite free end of the other plate for attaching the other end of the strap-length thereto, a latch slideable on said last-named plate at a point adjacent its connection with the buckle, resilient means for sliding the latch to positively engage it with the opposite plate when said plates are folded into overlying relation, and manually-operable means for releasing the latch to unlock the plates to permit them to be opened into extended relation.

5. In a device of the type specified, the combination of a pair of plates hinged together at one of their ends, means at the opposite free end of one of the plates for permanently attaching it to a strap, band or bracelet, means at the free end of the other plate for adjustably attaching the other end of the strap-length thereto, one of said plates formed with a slot, a housing on the opposite plate, a latch slideable in said housing and formed with a catch projecting therethrough to adapt it to engage the edge of the slot in the other plate, and means on the latch projecting through the end of the housing to adapt it to be engaged by the finger to slide the latch to unlock the catch to permit the plates to be opened into extended relation.

In testimony whereof I affix my signature.

ALMYR L. NEWMAN.
